Application April 13, 1937, Serial No. 136,571
 In Czechoslovakia April 17, 1936

2 Claims. (Cl. 42—75)

My invention relates to automatic firearms with the barrel supported in the frame for ready exchange.

It is an object of my invention to provide means for so supporting the barrel in the frame at a point between the breech and muzzle, that the barrel can be readily exchanged and replaced.

According to this invention the means for supporting the barrel are so arranged on the barrel and the frame that when the barrel is mounted in place on the frame, they interlock and lock the barrel on the frame, while, when the barrel shall be exchanged, they form an abutment for the tilting of the barrel about the point of support near the muzzle, at the same time allowing the barrel to be moved in the longitudinal direction of its axis.

In firearms, in which the barrel is arranged for sliding motion relative to the frame, the supporting and locking means also serve to guide the barrel.

In the drawing affixed to this specification and forming part thereof a firearm embodying my invention is illustrated diagrammatically by way 25 of example.

In the drawing

Fig. 1 is a side elevation, partly in axial section, of the frame and the barrel mounted therein.

Fig. 2 is a similar view illustrating the way in 30 which the barrel is removed from the frame.

Fig. 3 is a cross section, drawn to a larger scale of the frame and barrel on the line III—III in Fig. 1.

Referring to the drawing, 1 is the barrel and 35 11 is the frame. 3, 3 are ribs on the breech end of the barrel extending at right angles to the barrel axis and 4, 4 are notches in the breech end of the movable breech case 5 mounted in the frame 11, which notches extend in parallel to the 40 ribs 3 on the barrel. 13, 13 are a pair of ledges on the inner sides of the forward end on the frame 11, said ledges extending in parallel to the barrel axis on either side of the barrel. 10a, 10b are pairs of lugs mounted on the barrel and extending substantially at right angles to and above and below the barrel axis, respectively, said lugs being spaced to embrace the ledges 13 on the frame, when the barrel is mounted in the frame. The lower lugs 10a are arranged forward of the 45 upper lugs 10b. 16, 16 are a pair of vertical projections mounted in spaced relation on the cross piece 17 connecting the two walls of the frame 11 and 15 is a lug extending downwardly from the bottom of the barrel and fitting in 50 between the pair of ledges 16.

The lugs 10a and 10b are arranged in staggered relation so that the front ends of the lugs 10b are spaced the distance z from the rear ends of the lugs 10a.

When it is intended to replace the barrel, the breech end which is interlocked with the body of the arm or the movable breech by means similar to those shown in French patent specification No. 733,153, is unlocked and the muzzle end is depressed and tilted about the forward bottom edges 18 of the lugs 10b resting on the ledges 13, until the ribs 3 are free of the notches 4, the breech end of the barrel moving in the direction of arrow p, whereupon the barrel can be pulled out in longitudinal direction as indicated by the arrow q, being thus disengaged from the ledges 13.

Obviously the means for supporting the barrel in the frame according to this invention may be applied to firearms of widely different types with stationary as well as with sliding barrel. In the latter case the means for supporting the barrel between the breech and muzzle ends may form guides for the movable barrel.

I wish it to be understood that I do not desire 25 to be limited to the exact details of construction shown and described for obvious modifications will occur to a person skilled in the art.

I claim:

1. In a fire arm in combination, a gun body 30 formed with an axially extending recess, a barrel seated in said recess, interlocking means on said body and the breech end of said barrel to hold said breech to said body with its breech end supported for ready removal of the breech end 35 of said barrel in vertical direction, two inwardly directed horizontal ledges facing each other on the inner walls near the muzzle end of said recess, and two pairs of outwardly directed horizontal ledges on said barrel, one pair extending 40 above, the other below the ledges fixed to the inner walls of said recess, when the barrel is seated in said recess, said pairs of ledges being arranged in staggered relation, the lower pair extending forward of the vertical plane containing the front edge of the upper pair.

2. In the fire arm of claim 1, means for centering the barrel on the bottom of the body comprising a vertically extending ledge on one and a pair of spaced vertically extending ledges on the other of the coaxing parts, said three ledges being arranged to interlock when the barrel is seated in the gun body.

VÁCLAV HOLEK. 55
